UNITED STATES PATENT OFFICE.

GEBHARD KOEB, OF SPRINGFIELD, OHIO, ASSIGNOR OF ONE-HALF TO
JACOB B. KORN, OF SAME PLACE.

STOVE-PIPE COLLAR.

SPECIFICATION forming part of Letters Patent No. 374,974, dated December 20, 1887.

Application filed March 7, 1887. Serial No. 230,002. (No model.)

To all whom it may concern:

Be it known that I, GEBHARD KOEB, a citizen of the United States, residing at Springfield, in the county of Clark and State of Ohio, 5 have invented certain new and useful Improvements in Stove-Pipe Thimbles, of which the following is a specification, reference being had therein to the accompanying drawings.

10 This invention is an improvement in stove-pipe thimbles; and it consists, essentially, in combining a metallic band or wire with the collar of the thimble, and in passing it round the collar and providing it with fastening devices, so as to draw its ends together, contract the collar, and cause it to bind the pipe and prevent it from projecting into the flue too far, which would obstruct the draft; and it also prevents it from coming out and dropping down, which would be liable to cause 20 fire.

In the accompanying drawings, forming a part of this specification, and on which like reference-letters indicate corresponding parts, 25 Figure 1 is a sectional view of the wall and of my improved thimble, as also a view of the cap in elevation and removed; Fig. 2, a like view of the wall, showing the thimble and a section of pipe in side elevation; Fig. 3, a 30 face view of the thimble, and Fig. 4 a sectional view of a modification in the manner of securing the collar to the ring portion of the thimble.

The letter A designates a chimney-wall or 35 other wall of a building, having the usual pipe-hole, B, therein, and the letter C the ring portion of the thimble, which fits snugly to the wall and prevents soot from accumulating between it and the wall.

40 As usually made, the rings are curved in cross section, the edge only touching the wall, while at the inner circumference thereof they stand away from it. This allows soot to gather and to work its way out and then fall 45 upon the floor beneath.

The letter D refers to the collar, the same being fitted to the ring, secured in any desired manner, and extended some little distance beyond it, so as to enter the pipe-hole 50 in the wall and act to support the ring additionally to the nails or other fastenings, E, or to hold it entirely when such fastenings are not used. The collar, by preference, has its

outer edge turned outward to form a flange, F.

The collar is also slotted at several points, as seen at G, so as to allow its diameter to be contracted by a band, H, which encircles it, and which has a fastening by which it is drawn tightly upon the collar. The fastening 55 consists in bending the ends of the band H outward, and providing the ends with holes, and with a bolt and nut, I, or thumb-screw. The flange F prevents the band H from slipping off the collar. When the band is drawn, the 60 collar is contracted, as already suggested, and the stove-pipe is consequently clamped and firmly held. This connection also prevents the chimney and the room from communicating through the space so frequently existing 65 between the pipe and thimble. The band may vary in shape in cross-section; but the flat band is preferred.

In Fig. 4 I have shown the collar provided with an annular groove or depression, into 70 which fits a corresponding head, J, extending inwardly from the ring C, the ring being also provided with a flange, K. The cap L (shown in side elevation in Fig. 1) serves to close the pipe-hole in the wall when the pipe is not in 75 use; and it consists of a sleeve, M, which fits within the collar D, and is held therein in the same manner that the pipe is held therein—namely, by the band H being contracted. At N the sleeve M is slotted, which permits of 80 the sleeve being compressed, so as to more readily enter the collar, if such should be necessary. The letter O refers to the head of the cap.

Having thus fully described my invention, 85 what I claim as new, and desire to secure by Letters Patent, is—

In a pipe-thimble, the combination, with the ring portion fitted against the wall and a collar fitted thereto, having its outer edge turned outward to form a flange and slotted 90 at intervals, of a band fitted round it, held from slipping or working off by the flange, and having its ends bent outward to receive a fastening-bolt.

In testimony whereof I affix my signature in presence of two witnesses.

GEBHARD KOEB.
